UNITED STATES PATENT OFFICE.

BONHAM GALLAND, OF NEW YORK, N. Y.

DESIGN FOR A FABRIC.

SPECIFICATION forming part of Design No. 16,163, dated July 14, 1885.

Application filed April 28, 1885. Term of patent 14 years.

To all whom it may concern:

Be it known that I, BONHAM GALLAND, a citizen of the United States, residing at New York, in the county and State of New York, have invented and produced a new and original Design for a Fabric, of which the following is a specification, reference being had to the accompanying drawing, forming part hereof.

The figure represents my design.

10 Heretofore it has been customary to mark cloth or similar fabrics, usually produced in great lengths, by transverse lines extending the entire width of the fabric, which are set at uniform distances apart.

15 The leading feature of my design is, as shown in the illustration, the fabric provided with rectangular marks running parallel to

the edge of the fabric and set at equal distances apart.

A represents the bolt of material. B B signify a series of rectangular marks running the entire length of the fabric near its edge and parallel therewith, which are equidistantly disposed.

25 I claim—

The design for a fabric having a series of rectangular marks near its longitudinal edge and parallel thereto, which are set at uniform distances apart, as shown and described.

BONHAM GALLAND.
